(57) **CLAIM**

I claim the ornamental design for a vehicle side mirror, as shown and described.

DESCRIPTION

FIG. 1 illustrates a front perspective view of the present invention.

FIG. 2 illustrates a front planar view of the present invention.

FIG. 3 illustrates a rear planar view of the present invention.

FIG. 4 illustrates an interior side planar view of the present invention.

FIG. 5 illustrates an exterior side planar view of the present invention.

FIG. 6 illustrates a top side planar view of the present invention.

FIG. 7 illustrates a bottom side planar view of the present invention; and,

FIG. 8 illustrates a front perspective view of the mirror mounted on a vehicle.

The drawings set forth a unique design for a vehicle side mirror.

The broken lines shown in the drawings represent portions of the vehicle side mirror and attachments that form no part of the claimed design.
